CLAIM

The ornamental design for a telescope mount, as shown and described.

DESCRIPTION

FIG. 1 is a right perspective view of the telescope mount, showing our new design;

FIG. 2 is a left perspective view thereof;

FIG. 3 is a side elevational view of the right side thereof;

FIG. 4 is a side elevational view of the left side thereof;

FIG. 5 is a back elevational view thereof;

FIG. 6 is a front elevational view thereof;

FIG. 7 is a top plan view thereof; and,

FIG. 8 is a bottom view thereof.

The broken line showing of the tripod legs in FIGS. 1–8, the broken line showing of the telescope tube in FIGS. 3 and 4, the broken line showing of the connector panel in FIGS. 1, 3 and 5–7 and the broken line showing of internal mount structures in FIG. 8 are for illustrative purposes only and form no part of the claimed design.

1 Claim, 8 Drawing Sheets
